CLAIM

The ornamental design for a pillow, as shown and described.

DESCRIPTION

FIG. 1. Is a front view of the pillow showing my new design.
FIG. 2 is a back view thereof;
FIG. 3 is a left side view thereof;
FIG. 4 is a right side view thereof;
FIG. 5 is a top view thereof;
FIG. 6 is a bottom view thereof;
FIG. 7 is a bottom perspective view thereof; and,
FIG. 8 is a top perspective view thereof.

1 Claim, 4 Drawing Sheets---
